UNITED STATES PATENT OFFICE

101,925

DESIGN FOR A RADIO LIGHT CLOCK

Mark M. Thompson, Sr., Atlantic, Iowa

Application May 9, 1936, Serial No. 62,563

Term of patent 7 years

To all whom it may concern:

Be it known that I, Mark M. Thompson, Sr., a citizen of the United States of America, residing at Atlantic, county of Cass, and State of Iowa, have invented a new, original, and ornamental Design for a Radio Light Clock, of which the following is a specification, reference being had to the accompanying drawing, forming a part thereof.

Figure 1 is a perspective front view of a radio light clock showing my new design.

Figure 2 is a side view.

Figure 3 is a top plan view.

The numerals shown on Figure 1 are merely representative of those numerals which would appear there from time to time.

I claim:—

The ornamental design for a radio light clock as shown and described.

MARK M. THOMPSON, SR.
